UNITED STATES PATENT OFFICE.

WILLIAM S. KEARNS, OF DULUTH, MINNESOTA, ASSIGNOR, BY DIRECT AND MESNE ASSIGNMENTS, OF ONE-FOURTH TO HUGH B. SMITH, OF ST. PAUL, MINNESOTA, AND ONE-HALF TO PETER WERTZ, OF PITTSBURGH, PENNSYLVANIA.

GREASE-CUP FOR LOCOMOTIVES.

1,375,703.

Specification of Letters Patent. Patented Apr. 26, 1921.

Application filed April 14, 1920. Serial No. 373,751.

To all whom it may concern:

Be it known that I, WILLIAM S. KEARNS, a citizen of the United States, residing at Duluth, in the county of St. Louis and 5 State of Minnesota, have invented certain new and useful Improvements in Grease-Cups for Locomotives; and I do hereby declare the following to be a full, clear, and exact description of the invention, such as 10 will enable others skilled in the art to which it appertains to make and use the same.

My invention has for its object to provide an improved grease cup for locomotive main and side rods, and to such ends, generally stated, the invention consists of the 15 novel devices and combinations of devices hereinafter described and defined in the claims.

In grease cups of this character, it is the 20 common practice to thread the plungers or followers into the cups and to lock them by nuts; but the nuts are liable to become loosened, and when this takes place, the plungers loosen up and work out of place 25 and are frequently lost. Moreover, it is the practice to provide the grease cups with threaded shanks that are screwed into the straps of the rods, and these, also, are liable to become loose.

30 My invention provides an extremely simple and highly efficient lock which will positively secure the grease cup to a strap and prevent backward rotation of the threaded follower in the grease cup.

35 The invention is illustrated in the accompanying drawings wherein like characters indicate like parts throughout the several views.

Referring to the drawings:

40 Figure 1 is a side elevation showing the improved grease cup and lock applied to the strap of one of the rods of the locomotive;

45 Fig. 2 is a plan view of the parts shown in Fig. 1, some portions being broken away;

Fig. 3 is a section on the line 3-3 of Fig. 2;

Fig. 4 is a side elevation of the follower;

and

50 Fig. 5 is a plan view of the follower.

The numeral 6 indicates one of the rod straps and the numeral 7 the bearing brasses.

The numeral 8 indicates the grease cup,

the upper portion of which is internally 55 screw-threaded to receive the externally screw-threaded follower or plunger 9. The cup 8 has an outstanding stop flange 11 and below the same has an externally threaded portion 12 that is screw-threaded into the 60 strap 6, leaving the entire lower end of the grease cup open. At its outer end, the follower 9 has a flattened rib 13 that adapts it to be easily turned, either by the fingers, or by a wrench. At one side, a ratchet-like 65 groove 14 is cut through the external threads of the follower 9 from end to end thereof.

The lock is made from a single piece of spring wire 15, the upper portion of which 70 is bent U-shaped to increase the resilience thereof and is terminated in a flattened pawl-like end 16. The lower end of the lock spring 15 is tightly driven or forced through aligned perforations in the flange 11 75 of the grease cup and in the strap 6, the latter perforation being preferably adjacent to the threads of the lower portion 12 of the cup. The flattened end 16 of the lock spring works through a perforation in one 80 side of the grease cup and is engageable with the ratchet-like groove 14 of the follower, so as to positively prevent backward rotation of the follower beyond a possible 85 partial rotation. When it is desired to screw the follower out of position, or backward, the pawl-like end 16 of the lock can be easily retracted by applying the finger to the bent upper portion of said lock strap.

As is obvious, the following can be freely 90 rotated in a direction to move the same downward, or farther into the cup, but can not possibly work loose or get displaced from the cup. This simple lock, moreover, 95 may be applied at very trifling cost, and, as stated is efficient in performing both of its locking functions above noted.

What I claim is:

1. The combination with a strap, or the like, of a grease cup having a shank that is 100 screw-threaded into said strap, the interior of said cup being screw-threaded, a follower working with threaded engagement in said cup and having a ratchet-like groove cut longitudinally through its threads, and 105 a lock formed from a single piece of spring wire and provided with a curved upper end terminating in a pawl-acting end that works

through a perforation in said cup and is engageable with the groove of said follower to prevent backward rotation thereof, the other end of said lock spring being passed 5 through a projecting portion of said cup and extended into said strap to thereby lock said cup to said strap.

2. The combination with a connecting rod strap, or the like, and a grease cup applied thereto, said grease cup being internally threaded, of a follower working with threaded engagement in said cup, and a lock for said follower in the form of a spring rod anchored to said cup and strap 10 to prevent relative rotation thereof and having a pawl-acting end working through a perforation in said cup and engageable

with the threads of said follower, the said follower having a ratchet-like groove cut longitudinally through its threads. 20

3. The combination with a bearing element, of a grease cup having screw-thread attachment thereto, a follower in said cup having screw-threaded engagement therewith, and a single member for locking said cup to said bearing element and said follower in variable longitudinal positions in said cup. 25

In testimony whereof I affix my signature in presence of two witnesses.

WILLIAM S. KEARNS.
